UNITED STATES PATENT OFFICE.

THOMAS SHAW, OF PHILADELPHIA, PENNSYLVANIA.

WINTER-SOLE FOR BOOTS AND SHOES.

SPECIFICATION forming part of Letters Patent No. 241,733, dated May 17, 1881.

Application filed December 1, 1880. (No model.)

To all whom it may concern:

Be it known that I, THOMAS SHAW, of the city and county of Philadelphia and State of Pennsylvania, have invented a new and Improved Winter-Sole for Boots and Shoes; and I hereby declare the following to be a full, clear, and exact description of the same, reference being had to the accompanying drawing, and to the letters of reference marked thereon.

10 My invention consists in the provision of numerous isolated metallic points projecting slightly from an elastic sole of a shoe, arranged in the manner and for the purpose as herein-after described.

15 The object of the invention is to furnish a sole for boots and shoes that offers great frictional resistance to sliding motion when in contact with ice, whether wet or dry, to avoid the serious accidents that usually attend per-

20 pedestrians while traveling upon icy sidewalks.

On reference to the accompanying drawing, which forms part of the specification, the figure represents a section of a sole of a boot, of which—

25 *a* is the leather portion, and *b* represents a rubber sole secured to the ordinary leather sole by nails or cement, or by any of the ordinary methods of securing gum soles to leather soles. The gum sole *b*, preparatory to being

30 secured to the leather sole, is provided with numerous metallic points, *a*, which points are formed and secured in position by driving tacks, nails, screws, or staples through said gum sole, all from the inner side of said gum sole, so that when in place on the leather sole of a leather boot, or the gum sole of a gum boot, the heads of said tacks, nails, &c., will

35 rest between the soles, as shown, thus preventing the escape of said nails, and offering a foundation-support for the nail-heads when in use.

The operation of the metallic points in combination with the gum is favorable for walking upon carpets, with little or no injury to the carpet, as it will be observed that the metallic points are nearly or quite flush with the under surface of the gum, when walking upon soft material, as carpets, &c., whereas when any

hard substance, as stone or ice, is trodden upon the gum yields slightly around said points, 50 causing the same to project slightly, and thus offer resistance to any sliding movement, which resistance is proportionate to the number of metallic points, all operating in the same manner, as occasion requires. Thus at one and the same time are secured a durable sole for boots and shoes, and an effective ice-creeper.

It will be observed that the nails, with their heads resting against the sole of the shoe, are susceptible of considerable lateral motion, independent of each other, within the limits of the elasticity of the gum sole, the head of the tack or nail serving as a kind of pivot to permit a rolling motion, which is highly favorable for preserving the metallic points against 65 breakage.

It will be evident that these soles can be variously fashioned, and can be manufactured from various elastic materials, and secured in position by various methods, without any alteration in the result. I therefore do not wish to confine myself to any exact materials, shape, or method of fastening.

I am aware that metallic frames with serrated projections have been combined with 75 rubber soles, and do not claim, broadly, the combination of a rubber sole and metallic points, my invention consisting in the use of independent nails whereby to obtain a secure hold without detracting from the flexibility of 80 the sole. The isolation of the points is important, as thereby each can have a slight vibrating motion independent of the others, permitting them to yield without breaking and without necessarily bending the sole. 85

I claim—

A sole for shoes, &c., consisting of a sole of elastic material and a series of studs or tacks embedded in said sole, their heads at the inner side and their points flush, or nearly so, 90 with the outer side of said sole, all as set forth.

THOMAS SHAW.
